US0D1036902S

(12) **United States Design Patent** (10) Patent No.: **US D1,036,902 S**
 Dean et al. (45) Date of Patent: ** Jul. 30, 2024

(54) **BEVERAGE CONTAINER**

(71) Applicant: **The Coleman Company, Inc.**, Wichita, KS (US)

(72) Inventors: **Matthew Dean**, Parchment, MI (US); **Marcus Hamilton**, Kalamazoo, MI (US)

(73) Assignee: **The Coleman Company, Inc.**, Wichita, KS (US)

(**) Term: **15 Years**

(21) Appl. No.: **29/818,149**

(22) Filed: **Dec. 7, 2021**

(51) LOC (14) Cl. **07-01**

(52) U.S. Cl.

USPC **D7/523**

(58) **Field of Classification Search**
